UNITED STATES PATENT OFFICE.

BUTLER AMES, OF LOWELL, MASSACHUSETTS.

ELECTROMAGNETICALLY-OPERATED HORN.

1,231,835.

Specification of Letters Patent.

Patented July 3, 1917.

Application filed February 1, 1915. Serial No. 5,389.

To all whom it may concern:

Be it known that I, BUTLER AMES, citizen of the United States, residing at Lowell, in the county of Middlesex and State of Massachusetts, have invented certain new and useful Improvements in Electromagnetically-Operated Horns, of which the following is a specification, reference being had therein to the accompanying drawings.

My invention relates to electro-magnetically operated percussion diaphragm horns, and is embodied in means for adjusting the electro-magnet and its vibrator in relation to each other and to the button of the diaphragm, so that the vibrations of the diaphragm and those of the vibrator armature of the electro-magnet will, within workable limits, be synchronous, and in opposite directions, notwithstanding great variations in the frequency of the electrical current, and in its voltage; for example, by means of my invention, the horn will operate successfully where the electrical current generated by the magneto, is also being employed for electric lighting, and ignition purposes, and its voltage is consequently greatly reduced; and also where the frequency of the alternating current may vary from, say, 3200 to 32000 per minute, as where the engine driving the generator, revolves at a speed changing from 200 to 2000 revolutions per minute, and the generator has a frequency of 16 for each revolution of its armature.

Its utility will become still more evident when one considers that electro-magnets and vibrators, supposed to be alike, do as a matter of fact differ from each other in magnetical and electrical efficiency; and that, while a horn, electro-magnet and vibrator might be fixed in proper relations successfully to operate with an alternator generating a current having certain frequencies and voltage, yet it would be valueless were it used without change, in connection with a current different in frequency and voltage, for the vibrations of the diaphragm and the vibrator would not be in time and would not be in opposite directions.

In fine, a horn embodying my invention may be adapted for use in automobiles having different engines, generators, and alternating currents having different frequencies and voltages.

In the drawings illustrating the principle of my invention and the best mode now

known to me of embodying the same in operative structure,

Figure 1 shows my invention in elevation, part of the associated horn being broken away for clearness.

Fig. 2 is a plan of the housing, showing ratchet and holes for retaining parts in adjustment; the vibrating unit having been removed.

Fig. 3 is a plan of the vibrating unit mounted in the housing.

The bell A, flange B, diaphragm C, button D, packing E, washers F, housing G are all, so are the electro-magnet H, core I and vibrator J.

The vibrator support 1 is secured to the base 2 of the core, and extends parallel with the magnets H until it reaches about the plane containing the poles of the magnet, 75 where it bends at right angles and extends outwardly a short distance where it is bent back upon itself and ends with a substantially parallel surface 3 upon which is mounted the vibrator J secured thereto by screws 4; the position of the vibrator being varied and determined by an adjusting screw 5 opposite a hole 5^a in the housing G and mounted in the support and controlling the distance between the vibrator and the poles of the magnet.

Axially fixed to the core I is a threaded adjusting rest 6 which is in screw engagement with an adjusting head 7 located in the longitudinal axis of the horn and housing, where it is retained by a shoulder 8 contacting the outside of the housing, and by a headed portion 9 within the housing, which confines by means of a washer 10, a flat spring ratchet 11 close to the bottom of the housing; a series of ratchet holes 12, Figs. 2 and 3, are arranged in the bottom of the housing, in a circle having said axis as a center, and designed to be engaged by projections 13 in the adjacent face of 100 the ratchet spring 11; the adjusting head 7, washer 10 and ratchet 11 being fixed together and rotatable in relation to the housing.

To prevent rotation of the vibrating unit, two pins 14, one on each side of the vibrator rest, are fixed in the flanged portion of the housing.

To use my invention, the coils of the electro-magnet are assumed to be connected with a generator of an alternating current that may be subjected to various loads such

as electric lighting, etc.; the generator being driven as by an internal combustion engine. The vibrator J is caused to press against the button D of the diaphragm C. This is brought about by turning the head 7 which causes the threaded rest 6 to move forward the vibrator unit, confined between the guide pins 14, and thus prevented from rotating. This pressure exerted by the bent vibrator against the button D of the diaphragm, causes the latter to be moved into a position slightly ahead of that it would occupy were it at rest and not engaged by the vibrator. The generator being in operation, the current is next allowed to energize the magnet H; the frequency of vibrations, and the stiffness of the vibrator spring and diaphragm causing the successive hammer blows of the vibrator upon the button of the diaphragm to follow with a rapidity and force that will prevent the diaphragm from returning to the plane it would occupy were it at rest. The vibrations of the vibrator and diaphragm being synchronous and opposite, the desired quality of sound results.

Now should the voltage of the alternating current be reduced, as by the use of some of the current for electric lighting purposes, the amplitude of vibration of the vibrator might be so reduced, due to the diminution of the strength of the magnetic field of the electro-magnet, that the percussion of the hammer vibrator, of the diaphragm would result in an injurious loss of sound. In such an event the adjusting screw 5 would, through the opening 5^a in the housing G, be so turned as to draw the vibrator nearer to the poles of the magnet, while the whole vibrating unit would be moved forward by operating the adjusting head 7, to restore the original tension between the vibrator and the diaphragm, as already explained. If these adjustments are right, the vibrator will strike a hammer blow upon the diaphragm with the same force as before, for the frequency remains the same, and the pull of the magnet is not changed, for although the magnetizing current is less in strength and hence there is less strength of magnetic field, yet, as the vibrator has been moved nearer the poles of the magnet, it is attracted with substantially the same force, so that the resulting sound due to the hammering of the vibrator is the same as before. By operating the horn at varying speeds of the generator, and with an alternating current varying in voltage, the operating parts of the horn can, by means of my invention, be given, and left in certain mean positions wherein the operating parts will cause the horn, under the varying conditions above suggested, always to produce the sound required, namely that flowing from the synchronous but opposite vibrations of the diaphragm and vibrator.

It is to be noted that in moving the adjusting head 7, the resistance of the projections 13 of the ratchet 11 to being moved out of the ratchet holes 12, has to be overcome; and that this resistance is sufficient to hold the ratchet and hence the vibrating unit in any particular adjustment.

Desiring to protect my invention in the broadest manner legally possible,

What I claim is:

In an electro-magnetically operated percussion horn having a combined housing and flange, a diaphragm, an electro-magnet, a vibrator, a base for the electro-magnet, an adjustable head rotatably mounted in the housing, and in the longitudinal axis of the horn, said head being manually operated outside of said housing, a threaded adjusting rest fixed to said base of said magnet, and rotatably mounted in, and in relation to, said head, and in said longitudinal axis, a spring ratchet fixed to said head and having a projection to slidably engage ratchet holes in the bottom of said housing, and means to prevent the rotation of said electro-magnet in relation to said housing, all designed to allow an adjustment of said magnet in relation to the diaphragm, without a removal of the housing from the flange.

In testimony whereof I hereunto affix my signature in the presence of two witnesses.

BUTLER AMES.

Witnesses:
